UNITED STATES PATENT OFFICE.

WILLIAM LAWLESS, OF QUENEMO, KANSAS.

WASHBOARD-CLAMP.

1,132,362.

Specification of Letters Patent. Patented Mar. 16, 1915.

Application filed February 25, 1914. Serial No. 820,914.

To all whom it may concern:

Be it known that I, WILLIAM LAWLESS, a citizen of the United States, residing at Quenemo, in the county of Osage and State 5 of Kansas, have invented certain new and useful Improvements in Washboard-Clamps; and I do hereby declare the following to be a full, clear, and exact description of the invention, such as will enable others skilled in 10 the art to which it appertains to make and use the same.

This invention relates to wash board clamps, designed for the purpose of holding a wash board firmly within a wash tub in position for use, and one of the principal objects of the invention is to provide a device of simple construction which will hold a wash board at the desired inclination relatively to the wash tub to render the washing 20 easy.

Another object of the invention is to provide a wash board clamp in which means are provided for securing the same to wash tubs of different sizes and to wash boards of different dimensions, and which will hold the board at any required inclination, and support the board firmly in adjusted position.

These and other objects may be attained by means of the construction illustrated in 30 the accompanying drawings, in which,

Figure 1 is a sectional view taken through a wash tub and showing a wash board clamp made in accordance with this invention secured to the upper edge of the wash tub and supporting a wash board, Fig. 2 is a view in elevation and partial section of a clamp made in accordance with this invention and made on a larger scale than Fig. 1, Fig. 3 is a perspective view of the clamp with portion 35 of the wash board clamp broken away, Fig. 4 is a sectional view taken on the line 4—4 of Fig. 2, Fig. 5 is a detail sectional view taken on the line 5—5 of Fig. 3.

Referring to the drawing the numeral 1 45 designates a wash tub of the usual or any suitable type, to which a wash board 2 of any suitable character or construction is shown clamped within the wash tub 1 at the desired inclination to suit the person doing 50 the washing.

The clamp or device for connecting the wash board to the wash tub, comprises a bar 3 curved to extend over the upper edge of the wash tub 1 with its terminal end extending through a slot 4 in the supporting

member 5, having a depending member 6, through which a screw 7 extends, the end 3^a of the clamp projects through a slot 4^a in the member 5. The screw 7 projects through an enlarged and threaded portion of the clamp member 3, and bears against the base portion 5 of the support. The slots 4 and 4^a serve as a guide for the clamping bar 3, and the enlarged portion 8 through which the screw 7 passes serves to give a long bearing 65 to the said screw. The other jaw of the clamp member 3 projects downward within the tub as shown at 9, and is then extended to form a horizontal arm 10. Projecting at an inclination from the arm 10 is a clamp 70 support 11 provided with an elongated slot 12. A bar 13 is adjustably clamped by means of a screw 14 to the inclined portion 11, said screw extending through the slot 12 and permitting adjustment of the bar 13. 75

The wash board clamps are adjustably connected to the bar 13, said clamps each comprising an L-shape member 15 provided with a slot 16 through which the bolt 17 extends, said bolt also extending through a 80 perforation in the bars 13 and provided with a nut 18 at their threaded ends. The members 15 are provided with an angular portion 19 and overhanging lugs 20. Thumb screws 21 extend through the members 15 in 85 line with the overhanging lugs 20 to clamp a wash board 2 in place at the required inclination in a wash tub.

From the foregoing it will be obvious that a wash board 2 of any width may be quickly 90 clamped at the opposite edges by means of the screws 21 and the overhanging lugs 20, and that the wash board may be secured at any required inclination by adjustment of the screw 14 in the slot 12, while the entire 95 device may be quickly connected to the upper edge of a wash tub by means of the thumb screw 7.

The invention is simple in construction, can be manufactured at comparatively low 100 cost, is reliable and efficient for its purpose, cannot readily get out of order, and can be quickly placed in position to hold the wash board firmly in place in the wash tub to render the operation of washing comparatively 105 easy.

Various changes may be made in the details of construction without departing from the spirit and scope of the invention as defined in the claim.

What is claimed is:—
A wash board clamp comprising a curved U-shaped member adapted to fit over the upper edge of a tub, a guide mounted on one arm of said member and adapted to bear against the outer side of a wash tub, a screw extending through said guide, an arm extending downward from the curved member, a bar consisting of two sections, one adjustable upon the other, said bar being connect-

ed to the arm and an L-shaped member at the outer end of said sections for clamping a wash board.

In testimony whereof I affix my signature in presence of two witnesses.

WILLIAM LAWLESS.
